PROCESS OF MAKING TARTARIC ACIDS OR THEIR COMPOUNDS.

1,181,555.

Specification of Letters Patent.

Patented May 2, 1916.

Application filed July 21, 1910. Serial No. 573,057.

To all whom it may concern:

Be it known that I, MOOSHEGH VAYGOUNY, a citizen of the United States, residing at Berkeley, county of Alameda, and 5 State of California, have invented a new and useful Process of Making Tartaric Acids or Their Compounds, of which the following is a specification.

This invention relates to a process of 10 making tartaric acids or their compounds from glyoxylic acid or its compounds and has as its object the making of tartaric acids or their compounds in a more economical and efficient manner than heretofore.

15 My process relates to the reduction of glyoxylates under the influence of certain agents and under certain conditions whereby two glyoxylic molecules are caused to take up a one molecule of hydrogen, thereby resulting in tartaric acids or tartrates, as the case may be.

20 I shall hereinafter describe such a process in connection with the manufacture of racemic and meso-tartaric acids, although it may as well be practised in connection with the manufacture of the other tartaric acids as further derivatives.

25 In the following I describe, in connection with the accompanying drawing, a means illustrating a way of carrying out my process electrolytically, (that is using the electric current as the particular agent).

30 The drawing is a diagrammatic representation of a double compartment electrolytic cell, illustrating one means of carrying out my process electrolytically. It is intended to be illustrative only, as it is obvious that the particular apparatus used is not an essential feature of the process.

35 In the drawing, A indicates a suitable container which may be of any desirable non-conducting material, such as wood. The shape of it is immaterial. B indicates the cathode provided with suitable perforations B', and C indicates the cathode terminal. Of course the container A could be dispensed with and the cathode itself be formed into a cathode chamber, the exterior being insulated in some suitable manner and 40 the perforations B' in this case, omitted. I have found that the best cathodes to bring

about the reduction in question are made of those conductive materials which possess the quality of low over-voltage, such as copper, gold, nickel, silver, iron or carbon. Of 55 these, practice shows copper to be the most suitable in point of efficiency in operation combined with economy in installation. Other metals than those specified will yield tartaric acids more or less efficiently, but 60 owing to their higher over-voltages they tend to yield further reduction products so that there is relatively much less tartrate formed.

D indicates the anode and E the anode 65 terminal. The anode should be of some material not readily attacked under the conditions of use, and I have found platinum in the form of a gauze netting to be very satisfactory. F indicates a suitable dia- 70 phragm of any desirable material separating the cathode chamber from the anode chamber.

It is desirable, in carrying on the electrolytic reduction of a glyoxylate, to keep 75 the surfaces of the cathode clean and bright and to employ clear solutions. When insoluble cathodes are used, such as gold, carbon, etc., the glyoxylate solution may be strictly neutral, or nearly so, without affecting the brightness of the surfaces. However, when more easily soluble cathodes are used, such as copper cathodes, it is well to start the process with an electrolyte not

strictly neutral but preferably slightly alkaline, and to keep it in such condition throughout the duration of the reduction, if necessary. Under otherwise proper conditions, such a precaution will meet all requirements in this respect, as I have ob- 85

served that in such alkaline solutions the surface of the cathode remains bright and clean when once the process is started with it in this condition. Mechanical brightness (such as is obtained, for example, by buffing), as distinguished from mere chemical cleanliness, is an important condition in obtaining a full yield. If, for any reason, the cathode surfaces should lose their brightness, the cathodes should be removed from 90 the cell and cleaned or their surfaces renovated or brightened in any suitable way. 95 100

It must be understood that quite apart from its usefulness in preserving the brightness of the surfaces of the cathodes, the approximate neutrality, or slight alkalinity, 5 as the case may be, of the solution, is of importance in the production of the tartrates.

As an example of the practice of my process in connection with the electrolytic means disclosed, I give the following: 500 cubic 10 centimeters of a solution containing 32 grams of potassium glyoxylate, 20 grams of potassium sulfate and 0.5 gram of potassium hydroxid is introduced into the cathode chamber. For this quantity of solution and 15 this type of cell the cathode should preferably have a unilateral surface of about 200 square centimeters. About 60 cubic centimeters of a suitable electrolyte, which may be, for instance, a dilute acid such as a 5 per 20 cent. solution of sulfuric acid, is then introduced into the anode chamber.

The cathode solution being kept agitated by any suitable means, such as a suitably arranged stirrer or paddle or by utilizing the 25 cathode itself as a stirrer,—in order to prevent the yield in tartrates dropping too heavily in favor of further reduction products,—a direct current of about 4 amperes strength is caused to pass through the solution 30 from the anode to the cathode, the contents of the cell being cooled by any suitable means if necessary, so as to prevent the temperature of the solution from rising much above 20° to 25° centigrade. It should not 35 substantially exceed 40° centigrade. The distance between the anode and cathode may be about 1 to 1½ inches, in the example given, and the voltage under such conditions may be about 5 volts. As the current flows, the 40 glyoxylate is reduced to tartrate almost in theoretical quantities, the hydrogen tending to be generated at the cathode being absorbed during most of the operation. In about two hours and a half under the conditions 45 named, the reduction is complete, as is then evidenced by a brisk evolution of free hydrogen beginning on the cathode surfaces and the disappearance of glyoxylate. The solution is now withdrawn from the cell 50 and the excess of alkali (generally small) which is formed in the cathode chamber by reason of electrolytic phenomena, is neutralized with a part of the acid solution from the anode chamber, or with another solution 55 of a suitable acid if necessary. The resultant solution now consists of a substantially pure solution of a mixture of potassium sulfate, potassium tartrates (racemic and meso- 60 tartrates in about equal proportions) together with a very small proportion of potassium oxylate and glycolate. To this is now added a suitable precipitant of tartrate such as a calcium salt, preferably calcium sulfate (30 grams, that is, nearly the theoretical quantity) which is readily convert-

ed into calcium tartrates and precipitated as such. There is thus formed, of course, a corresponding quantity of potassium sulfate which remains in solution. The resulting calcium tartrates are then filtered off and 70 further worked up by any of the well known methods for the recovery and separation of the tartaric acids in free form, whence any other compound may be derived. For example, the calcium tartrates may be decomposed by sulfuric acid thus forming calcium sulfate, which may be filtered off, and tartaric acids, which latter, in turn, may be evaporated to crystallization, if desired, in which case the racemic acid separates out 80 almost completely first, leaving meso-tartaric acid in the mother liquor.

During the process of reduction the most satisfactory temperature at which the solution may be maintained is about 20° centigrade, and for the satisfactory working of the process the temperature should not be allowed to rise much above 30° to 40° centigrade, nor to fall much below 10° centigrade.

The concentration of the solution of the glyoxylate employed should be moderate, 90 10 to 20% having been found the most satisfactory. A solution of above 20% glyoxylate tends to be uneconomical in practice because the glyoxylate employed then tends to take part too freely in the conduction of the current, being thereby carried into the anode compartment and there decomposed. As this tendency, even in the case of very 100 much more dilute solutions, would still be too marked, it is advisable to introduce into the solution a certain amount of another electrolyte, such as a salt of an alkali metal, in the example given, potassium sulfate. By 105 so doing the potassium sulfate, being a far better conductor than the glyoxylate present, will diminish the number of glyoxylate ions carried into the anode compartment.

The current density on the cathode should 110 be kept between certain limits, as, for a given rate of agitation of the solution, the current density for good yields in tartrates will be higher the more vigorous the mechanical agitation of the cathode solution. 115 The most satisfactory cathode density I find to be about 1 to 4 amperes per square decimeter of operative cathode surface for an ordinary agitation without having resort to violent stirring, as would be necessary in 120 case much higher current densities were employed.

While I have described in the foregoing a special form of cell which may be used in my process, it is obvious that in the commercial operation of the process other forms and larger apparatus may be used without departing from the principle of my invention, and I do not limit myself to the use of any particular form or kind of apparatus 125 130

in practising my process. It is further obvious that the character and size of the electrodes, the temperatures, the degree of concentration of the solutions employed, the 5 current strength and density and the manner or rate of agitation of the solutions may be varied within limits to suit the conditions of operation in commercial practice and I do not precisely limit myself in any of these 10 particulars.

Furthermore, while I have illustrated my process in connection with the use of potassium glyoxylate, which I have found to be preferable, other glyoxylates, such as sodium, ammonium or magnesium glyoxylates, 15 or hydrogen glyoxylate, or any derivative of glyoxylic acid in general, such as organic glyoxylates, for example ethyl glyoxylate, may be used, and I do not limit myself to 20 metallic glyoxylates. Where I use the term "glyoxylate" in the claims I intend to include any suitable glyoxylate, and where I use the term "alkali glyoxylate" I intend to include alkaline earth glyoxylates, such 25 as magnesium glyoxylate.

In the electrolytic way of practising my process hereinbefore described, which I prefer to use, the electric current is availed of as the agent instrumental in bringing about 30 the reduction of the glyoxylates to the tartrates. I do not, however, limit myself to that particular agent (except in the claims specifically designating it) as there are other agents which might be used for the same 35 purpose. The agent may be, for example, metallic couples introduced into the solutions kept under otherwise satisfactory conditions. Suitable couples would be a copper-iron couple, a copper-gold couple, an 40 iron-platinum couple, or many other similar couples, the object being to cause the addition of hydrogen to the glyoxylic molecules under proper conditions.

Another available group of agents comprises the use of hydrogen with certain metals having such physical properties as will render the element hydrogen labile, active and nascent, as it were, under the conditions above described toward the glyoxylates and reduce them to tartrates. As examples of such metals, I may mention platinum, palladium, gold, nickel, copper, etc., used in their spongy or colloidal states, for instance, in the presence of free hydrogen. 55

I believe I am the first to provide a commercially-operative process for the production of tartrates from glyoxylates.

I claim:

1. A process of making tartaric acids or 60 their compounds comprising the reduction, by an electric current, of a glyoxylate.

2. A process of making tartaric acids or 65 their compounds comprising the reduction, by an electric current, of a neutral or nearly neutral solution of a glyoxylate.

3. A process of making tartaric acids or 70 their compounds comprising the reduction, by an electric current, of an alkali glyoxylate.

4. A process of making tartaric acids or 75 their compounds comprising the reduction, by an electric current, of a neutral or nearly neutral solution of an alkali glyoxylate.

5. A process of making tartaric acids or 80 their compounds comprising the reduction, by an electric current, of potassium glyoxylate.

6. A process of making tartaric acids or 85 their compounds comprising the reduction, by an electric current, of a neutral or nearly neutral solution of potassium glyoxylate.

7. A process of making tartaric acids or 90 their compounds comprising the reduction, by an electric current, of a glyoxylate, neutralizing the resultant solution and reacting the same with a precipitant of tartaric acids.

8. A process of making tartaric acids or 95 their compounds comprising the reduction, by an electric current, of a neutral or nearly neutral solution of a glyoxylate, neutralizing the resultant solution and reacting the same with a precipitant of tartaric acids.

9. A process of making tartaric acids or 100 their compounds comprising the reduction, by an electric current, of an alkali glyoxylate, neutralizing the resultant solution and reacting the same with a precipitant of tartaric acids.

10. A process of making tartaric acids or 105 their compounds comprising the reduction, by an electric current, of a neutral or nearly neutral solution of an alkali glyoxylate, neutralizing the resultant solution and reacting the same with a precipitant of tartaric acids.

11. A process of making tartaric acids or 110 their compounds comprising the reduction, by an electric current, of potassium glyoxylate, neutralizing the resultant solution and reacting the same with a precipitant of tartaric acids.

12. A process of making tartaric acids or 115 their compounds comprising the reduction, by an electric current, of a neutral or nearly neutral solution of potassium glyoxylate, neutralizing the resultant solution and reacting the same with a precipitant of tartaric acids.

13. A process of making tartaric acids comprising the reduction, by an electric 120 current, of a neutral or nearly neutral solution of a glyoxylate, neutralizing the resultant solution, reacting the same with a calcium salt, filtering off the resulting calcium tartrates and decomposing the same 125 with an acid to liberate the tartaric acids.

14. A process of making tartaric acids comprising the reduction, by an electric current, of an alkali glyoxylate, neutralizing the resultant solution, reacting the same 130

- with a calcium salt, filtering off the resulting calcium tartrates and decomposing the same with an acid to liberate the tartaric acids.
- 5 15. A process of making tartaric acids comprising the reduction, by an electric current, of a neutral or nearly neutral solution of an alkali glyoxylate, neutralizing the resultant solution, reacting the same 10 with a calcium salt, filtering off the resulting calcium tartrates and decomposing the same with an acid to liberate the tartaric acids.
16. A process of making tartaric acids 15 comprising the reduction, by an electric current, of potassium glyoxylate, neutralizing the resultant solution, reacting the same with a calcium salt, filtering off the resulting calcium tartrates and decomposing 20 the same with an acid to liberate the tartaric acids.
17. A process of making tartaric acids comprising electrolyzing a neutral or nearly neutral solution of potassium glyoxylate, 25 neutralizing the resultant solution, reacting the same with a calcium salt, filtering off the resulting calcium tartrates and decomposing the same with an acid to liberate the tartaric acids.
- 30 18. A process of making tartaric acids or their compounds comprising the reduction of a glyoxylate in a solution free from organic acid other than glyoxylic acid.
19. A process of making tartaric acids or 35 their compounds comprising the reduction of a neutral or nearly neutral solution of a glyoxylate.
20. A process of making tartaric acids or 40 their compounds comprising subjecting glyoxylates in a solution free from organic acid other than glyoxylic to the influence of a suitable agent to cause them to unite with hydrogen simultaneously rendered available.
21. A process of making tartaric acids or 45 their compounds comprising subjecting a neutral or nearly neutral solution of a glyoxylate to the influence of a suitable agent to cause them to unite with hydrogen simultaneously rendered available.
- 50 22. A process of making tartaric acids or their compounds comprising the electrolytic reduction of a glyoxylate in the presence of a cathode not having high over-voltage.
23. A process of making tartaric acids or 55 their compounds comprising the reduction of a glyoxylate in an electrolytic cell provided with a copper cathode.
24. A process of making tartaric acids or 60 their compounds comprising the reduction of a glyoxylate at a temperature not exceeding substantially 40° centigrade.
25. A process of making tartaric acids or 65 their compounds comprising the reduction of a glyoxylate by an electric current of about from 1 to 4 amperes current density per square decimeter of operative cathode surface.
26. A process of making tartaric acids or 70 their compounds comprising the electrolytic reduction of a solution of a glyoxylate kept in agitation.
27. A process of making tartaric acids or 75 their compounds comprising the reduction, by an electric current, of a glyoxylate in the presence of an inorganic electrolyte.
28. A process of making tartaric acids or 80 their compounds comprising the reduction, by an electric current, of a glyoxylate in the presence of potassium sulfate.
29. A process of making tartaric acids or 85 their compounds comprising the reduction of a glyoxylate in an electrolytic cell provided with cathodes having bright surfaces.
30. In the manufacture of tartaric acids or 90 their compounds, a process which comprises submitting a glyoxylate to regulated reduction by active hydrogen.
31. In the manufacture of tartaric acids or 95 their compounds, a process which comprises submitting a non-acid solution containing a glyoxylic molecule to regulated reduction by active hydrogen.
32. In the manufacture of tartaric acids or 100 their compounds, a process which comprises submitting a glyoxylate to regulated electrolytic reduction.
33. In the manufacture of tartaric acids or 105 their compounds, a process which comprises submitting a non-acid solution containing a glyoxylic compound to regulated electrolytic reduction.
34. In the manufacture of tartaric acids or 110 their compounds, a process which comprises charging the cathode chamber of a divided cell with a non-acid solution containing a glyoxylate, charging the anode chamber with a suitable electrolyte and electrolyzing.
35. In the manufacture of tartaric acids or 115 their compounds, a process which comprises charging the cathode chamber of a divided cell with a non-acid solution containing a glyoxylate, charging the anode chamber with a suitable electrolyte and electrolyzing at a low temperature.
36. In the manufacture of tartaric acids or 120 their compounds, a process which comprises charging the cathode chamber of a divided cell with a non-acid solution containing a glyoxylate and potassium sulfate, charging the anode chamber with a suitable electrolyte and electrolyzing.
37. In the manufacture of tartaric acids or 125 their compounds, a process which comprises charging the cathode chamber of a divided cell with a non-acid solution containing a glyoxylate and a distributing conductor, charging the anode chamber with a suitable electrolyte and electrolyzing.
38. In the manufacture of tartaric acids 130

or their compounds, a process which comprises charging the cathode chamber of a divided cell with an alkalized solution containing glyoxylate and alkali salt, charging the anode chamber with a suitable electrolyte and electrolyzing.
